UNITED STATES PATENT OFFICE.

CARL O. BORKMAN, OF VICTOR, COLORADO.

DRILL FORGING AND SHARPENING MACHINE.

1,022,925.

Specification of Letters Patent.

Patented Apr. 9, 1912.

Application filed August 17, 1911. Serial No. 644,622.

To all whom it may concern:

Be it known that I, CARL O. BORKMAN, a citizen of the United States, residing at Victor, in the county of Teller and State of Colorado, have invented certain new and useful Improvements in Drill Forging and Sharpening Machines; and I do declare the following to be a full, clear, and exact description of the invention, such as will enable others skilled in the art to which it appertains to make and use the same.

This invention relates to improvements in drill forging and sharpening machines.

One object of the invention is to improve the drill forging and sharpening machine shown in United States Patent No. 991,698 granted to me May 9, 1911, whereby a stronger, more durable, and efficient construction is provided.

Another object is to provide a machine of this character having an improved construction and arrangement of drill forming dies and means for operating the same.

Another object is to provide simple and efficient means for operating the tool gripping jaws in opposite directions to open and close the jaws.

With these and other objects in view, the invention consists of certain novel features of construction, and the combination and arrangement of parts as will be more fully described and claimed.

In the accompanying drawings: Figure 1 is a plan view of my improved drill forging and sharpening machine; Fig. 2 is a side view thereof; Fig. 3 is an end view of the same; Fig. 4 is a detail perspective view of the movable member of the forming die and its holder; Fig. 5 is a similar view of one member of the drill drawing dies.

My improved drill forging and sharpening machine comprises a main supporting frame 1 having arranged in the central portion thereof a vertically disposed die holding and guiding recess 2 in the lower portion of which is arranged the stationary member 3 of an upsetting or forming die by means of which the cruci-form drill bits are formed. Slidably mounted in the recess 2 above the stationary member 3 of the die is a holder 4 to which is detachably and adjustably secured the upper movable member 5 of the forming die.

The holder 4 comprises a plate having offset side edges adapted to engage offset grooves in the side walls of the recess 2 and

having on its upper end a right angularly projecting lip or flange 6. The die member 5 is shown in the form of a flat rectangular block in the edges of which are formed matrices which are of the same shape but of different sizes, and in the present instance are shown as of cruci-form shape. The die member or block 5 is secured to the holder by means of a centrally disposed supporting bolt 7 which is adapted to be engaged with a circular passage 8 formed through the center of the die or block 5. The die or block 5 is held on the bolt 7 and in engagement with the back plate 4 and flange 6 of the holder by a transversely disposed fastening pin 9 which is inserted through the projecting outer end of the bolt 7. By thus arranging the die member 5 the fastening pin 9 may be removed and the member 5 slipped outwardly on the bolt 7 beyond the edge of the flange 6 whereupon the die member may be revolved to bring any of the matrices into an operative position after which the die member is pushed back on the supporting bolt 7 beneath the flange 6 of the holder and is secured in position by the fastening pin 9. The stationary die 3 is similarly mounted and adapted to be revolved to bring the desired matrix therein in position to coöperate with the corresponding matrix in the movable die. On the upper end of the die holder 4 are arranged parallel apertured lugs 10 which are pivotally connected to a die operating lever 11 pivoted at its inner end to a bracket 12 secured to one side of the frame and connected at its outer end by a link 13 to an equalizing lever 14 secured to the outer end of a piston rod 15 the piston of which is arranged in a cylinder 16 and adapted to be acted upon by any suitable fluid or hydraulic pressure whereby the piston rod is projected and the die holder 4 thus actuated to bring the die member 5 into operative engagement with the work.

In addition to the upsetting die, I also preferably provide a drill holding or clamping mechanism by means of which the shank of the drill is firmly held while the drill is being formed. The drill holding or clamping mechanism comprises clamping jaws 17 which are secured to the upper ends of operating links 18 the lower ends of which extend downwardly in the frame 1 and are connected to an operating lever 19 pivoted near one end in the frame 1 and to which

on each side of its pivotal connection are secured the lower ends of the links 18. By thus connecting the links 18 to the lever 19 it will be seen that when the lever is swung 5 downwardly the links 18 will draw the jaws 17 together and into engagement with the drill shank and when said lever is swung upwardly the links will move the jaws outwardly in opposite directions or out of engagement 10 with the shank of the drill thereby releasing the latter. The free or outer end of the lever 19 is connected by a short link 20 to the end of the equalizing lever 14 opposite that to which the link 13 of the die 15 operating lever is connected. By thus connecting the levers 11 and 19 with the piston rod 15 it will be seen that said levers will be actuated to simultaneously operate the forming dies and the drill holding mechanism. 20

Arranged in one end of the frame is an upsetting hammer 20' said hammer being slidably supported by a suitable guide 21 and having arranged in one end a dolly 22 25 which is adapted to be brought into forcible engagement with the end of the drill for the purpose of upsetting the same. With the opposite end of the hammer is engaged the outer end of a piston rod 23 on the inner 30 end of which is arranged a piston (not shown) but which is slidably and operatively arranged in a cylinder 24 and is adapted to be actuated by any suitable form of fluid pressure let into the cylinder 24. The upsetting hammer and its operating mechanism just described is constructed and arranged and is for the same purpose as the upsetting hammer shown and described in my previous patent hereinbefore referred to. 35

40 In addition to the forming and upsetting mechanism the invention further contemplates the drawing of the drills and to this end is provided on one side of the main frame with a laterally projecting die supporting frame 25 in which is arranged and suitably secured one member 26 of my improved drawing die, the other member 27 of which is suitably secured in an operating block or hammer 28 which is slidably 45 mounted between vertically disposed guide plates 29 secured to the frame 25 and connected at their upper ends by a cross bar 30 and between their ends by a cross bar 31. Between the bars 29 and the upper and 50 lower cross bars 30 and 31 is arranged a centrally disposed fluid pressure cylinder 32 with which is operatively engaged a piston rod 33, the outer end of which is secured to the operating block or hammer 28 whereby 55 the latter and the die member 27 are reciprocated to bring said die member into operative engagement with the stationary die member 26. Any suitable fluid pressure may be employed in the cylinder 32 and said pressure 60 is controlled by a suitable valve 34 to

which is connected an operating rod 35, said rod extending downwardly and having its lower end connected with a suitable foot treadle 36 arranged on and connected to the adjacent side of the extension 25 of the frame. 70

The members 26 and 27 of the drawing die are each constructed of a series of sections having shaped upper edges which, when brought into operative engagement with each other form matrices of the desired size and shape. The end sections of the die members have their outer surfaces inclined or formed on an angle whereby when the sections of the die members are assembled a substantially key-stone shaped structure is formed. The sections of the die members are secured together in operative position by a transverse connecting bar 37 which is adapted to be engaged with a similarly shaped groove or channel 38 formed in the outer sides of the sections of the die members as clearly shown in Fig. 5 of the drawing. The bar 37 when engaged with the recess 36 will hold the sections of the die members together in perfect alinement. The die members 26 and 27 are engaged with key-stone shaped recesses 39 formed in the frame 25 and hammer 28, and when so arranged said die members are securely fastened by suitable keys 40 arranged in the walls of the recesses 39 as shown. 80 90 95

From the foregoing description taken in connection with the accompanying drawings, the construction and operation of the invention will be readily understood without requiring a more extended explanation. 100

Various changes in the form, proportion and the minor details of construction may be resorted to without departing from the principle or sacrificing any of the advantages of the invention as claimed. 105

Having thus described my invention, what I claim is:

1. A drill forging and sharpening machine comprising a main frame, a drill forming die operatively mounted in said frame, a drill holding mechanism comprising a pair of slidably mounted drill gripping jaws, a pivotally mounted jaw operating lever, a pair of links adapted to connect said jaws with said lever on opposite sides of its pivotal connection whereby when said lever is operated, said jaws will be moved in opposite directions to bring the same into and out of operative engagement with the shank of the drill whereby the latter is held while being operated on by said forming dies, a dolly, and operating mechanism for said dolly. 110 115 120 125

2. A drill forging and sharpening machine comprising a supporting structure, a drill forming die comprising a stationary and a movable member, a holder to adjustably support and operate said moveable 130

member, a pair of drill gripping jaws, and means connected to simultaneously move said gripping jaws in opposite directions and to operate said movable die member, a dolly, and operating mechanism for said dolly.

3. In a drill forging and sharpening machine a supporting structure, dies mounted in said structure, a vertically movable holder for one of said dies, drill gripping jaws, and means for simultaneously actuating said die holder and moving said gripping jaws in opposite directions, a dolly, and operating mechanism for said dolly.

4. In a drill forging and sharpening machine, a supporting structure, a movable die holder mounted in said structure, drill gripping jaws, and means for actuating said gripping jaws and said movable die holder simultaneously, comprising an equalizing lever, a series of levers connected with said equalizing lever on one side of its fulcrum and with said movable die holder, another series of levers connected with said equalizing lever on the other side of its fulcrum and with said gripping jaws, and means for actuating said equalizing lever, a dolly, and operating mechanism for said dolly.

5. In a drill forging and sharpening machine, a supporting structure, a movable die holder mounted in said structure, drill gripping jaws, and means for actuating said gripping jaws and said movable die holder simultaneously, comprising an equalizing lever, a series of levers connected with said equalizing lever on one side of its fulcrum and with said movable die holder, an-

other series of levers connected with said equalizing lever on the other side of its fulcrum and with said gripping jaws, a fluid pressure cylinder, a piston mounted to reciprocate therein, and a piston rod connected at one end to said piston and at its other end to said equalizing lever, intermediately of the ends of said lever, a dolly, and operating mechanism for said dolly.

6. A drill forging and sharpening machine comprising a supporting frame, a drill forming die comprising a stationary and a movable member, a holder to adjustably support and operate said movable die member, a die operating lever connected with said holder, a fluid pressure cylinder, a piston rod operatively mounted therein, an equalizing lever connected with the outer end of said piston rod, a link to connect said equalizing lever with said die operating lever, a pair of drill gripping jaws, a pivotally mounted jaw operating lever, links to connect said jaws with said lever on the opposite sides of its pivotal connection, and a link to connect the outer end of said jaw operating lever with the equalizing lever on said piston rod whereby said jaws are operated simultaneously with the operation of the movable die member.

In testimony whereof I have hereunto set my hand in presence of two subscribing witnesses.
